(57) **CLAIM**

The ornamental design for a swimming pool light, as shown and described.

DESCRIPTION

FIG. 1 is a first perspective view of a swimming pool light showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is an exploded view of the swimming pool light thereof;

FIG. 10 is an exploded view of the swimming pool light thereof;

FIG. 11 is an enlarged view of the selected portion 11 in FIG. 1; and,

FIG. 12 is an enlarged view of the selected portion 12 in FIG. 9.

The dot-dash-dot broken lines represent the bounds of the claimed design while all other broken lines depict portions of the swimming pool light; none of the broken lines form part of the claimed design.
